BY MESNE ASSIGNMENTS, TO HOME CARBIDE GAS COMPANY, OF
CHICAGO, ILLINOIS, A CORPORATION OF SOUTH DAKOTA.

VALVE FOR ACETYLENE-GAS GENERATORS.

No. 828,598.

Specification of Letters Patent.

Patented June 19, 1906.

Application filed August 8, 1902. Serial No. 118,898.

To all whom it may concern:

Be it known that we, ISAAC W. HIGGS and HOKON HOYOSS, of Chicago, in the State of Illinois, have invented certain new and useful Improvements in Valves for Acetylene-Gas Generators, of which the following is a specification.

This invention relates to valves employed in regulating the admission of carbid to the water of the generator for the production of gas and in which the movement of the valve is controlled by means of a mechanical connection of the valve with the bell of the generator, whereby the lowering of the bell is utilized for operating the valve to let in a further supply of carbid.

It is the object of our improvement to provide an induction-tube with a rotary valve for the purpose which cannot be clogged so as to interfere with the feeding or stopped when open so as to allow the admission of carbid when not desired or otherwise fail to serve its intended purpose.

It is a further object to provide the induction-tube with means in connection with the valve for directing the stream of carbid upon the valve and protecting it from the full weight of the carbid in said tube.

To these ends we propose to provide the induction-tube, which connects the hopper or reservoir for the carbid with the water-tank of the generator, with a rotary valve having serial pockets each adapted to hold a quantity of the carbid to be discharged therefrom into the generator by the rotation of the valve and to provide the tube above the valve with a series of inclined baffle-plates designed to partially relieve the valve of the weight of the descending carbid and direct the current upon the valve in the direction of the revolution of its pockets.

We have attained these objects in the device constructed as illustrated in the accompanying drawings, in which—

Figure 1 represents in side elevation with broken portions a generator of the class described and shows the relation of the water-tank, gas-bell, carbid-reservoir, and induction-tube. Fig. 2 is an enlarged detail showing in perspective a ratchet and its rack-bar. Fig. 3 is an enlarged fragmentary view showing a vertical section taken centrally through that portion of the induction-tube where the

valve and inclined baffle-plates are located. Fig. 4 is a similar view taken on the line 4 4 55 of Fig. 3 and shows the parts as viewed at right angles to their position seen in Fig. 3.

In the drawings, A is the body of the generator; B, the gas-bell; C, the carbid reservoir or hopper, and D the induction-tube, 60 which connects the latter with the lower portion of the body, in which the water for the generation of the gas is contained. A pipe with stop-cock E for drawing off water and also a pipe at e for taking off the gas are provided, 65 and all of the parts so far mentioned are of the ordinary construction and arrangement, so that it is not deemed necessary to more particularly describe the same.

A shaft a is extended through the induction-tube D and journaled in the opposite walls thereof so as to rotate freely, means being provided for making gas-tight connections to prevent the escape of gas at the openings in the tube for the shaft. In the present 75 instance the induction-tube is rectangular in cross-section. The rotary valve is mounted on the shaft and adapted to suit the rectangular tube. The valve consists, preferably, of an octagonal central part a', with disks a² 80 at the ends having inturned flanges a³ at the periphery, and division-plates a⁴, secured to the central part and disks, so as to form pockets a⁵, closed at the sides and ends by the division-plates and disks and open at the 85 periphery except where covered by the flanges a³. The margins of the peripheral edges of the division-plates are preferably curved forward, as seen at a⁶. Said division-plates are distinguished from radial division- 90 plates in being placed off from the center or not in plane with the axis of rotation and inclined forward or in the direction of the revolution of the pockets and are distinguished from division-plates hinged to the valve-body so as to form peripheral pockets to be emptied by a turning of the plates on their 95 hinge in having fixed relation in the rotary valve and being arranged to be filled and emptied by the rotation of the valve itself. 100

The pockets are of the requisite size and have such arrangement with relation to the chute as to receive and control the delivery of all the carbid passing through the chute toward the generator, so that in operation all 105 of the carbid passes from the chute into the

pockets and is separately delivered therefrom to the generator as contradistinguished from being delivered to the generator through a throat or opening of a hopper or chute closed 5 by a weighted hinged gate, which is worked by a toothed feed-wheel, adapted to crowd the carbid against the gate.

Above the rotary valve is a series of baffle-plates *b*, placed at a downward slope of less 10 than forty-five degrees. The plates are designed to carry the greater portion of the weight of the carbid free of the valve, but allow the carbid to slide down as fast as taken by the pockets of the valve. The opening between 15 the baffle-plates *b* at their lower edges is less than the distance between the flanges *a*³, so that the stream of descending carbid will be centrally delivered in the pockets clear of said flanges, as seen in Fig. 4. To one of the 20 baffle-plates there is pivoted a cover *b'*, which is adapted to fit over the uppermost pocket at the time it is being filled, the weight of the cover being made sufficient to prevent the carbid from being spilled or forced over the 25 front side during the filling. The free end or portion of the cover rests on the outer edge of the division-plates between the flanges *a*³ when said plates are passing the cover, and when said cover slips off of the front side of a 30 pocket it rests down upon the stream of incoming carbid. The effect of this is to spread the carbid in the pocket toward the ends of the pocket under the flange *a*³ and to check the force of the current toward the filled 35 pocket and tend to turn it back toward the next approaching empty pocket.

A similar hinged cover *b*² is provided for the pocket next behind the topmost one. This is curved on the arc of the periphery of 40 the valve, so as to successively cover the pockets as they approach the opening between the baffle-plates *b*, through which they are filled. The cover *b*² is not regarded as of especial value in a stationary generator, 45 but would be of service in a generator used aboard railroad-cars or other moving conveyances where it would be subject to more or less shock or jar.

The lowermost of the baffle-plates *b* constitutes, in effect, a spout or chute for directing the stream of carbid out from the wall of the tube and gently down upon the rotary valve in the direction of the revolution of its 50 pockets.

55 The discharge end of the chute is placed or arranged at or about the intersection of a horizontal plane tangent to the top of the circle described by the rotary valve, with a vertical plane coincident with the vertical 60 position of the pocket division-plates when adjacent to said horizontal plane. With the chute having such relation with the pockets the force of gravity upon the carbid passing from the chute into the pockets is never sufficient 65 to cause the carbid to rise above and

run over the rear side of the pockets, or any pocket, into the generator at any phase of the revolution, or to rise high enough in the rear of the pockets to come in contact with the cover *b*² or with the chute, or to be caught 70 between its lower end and the rear side of the pocket when carried forward in the pocket passing close under the chute. The invention is distinguished by this relation of these parts for securing the results of preventing 75 any such overflow backward of the valve and preventing obstruction to the free movement of the valve by particles of carbid getting caught between it and the chute or being carried by the pocket in rubbing contact with 80 a relatively stationary part of the apparatus. In the revolution the rear side of the pockets at the peripheral margin, as seen at *e'*, Fig. 3, is brought sufficiently behind the discharge end of the chute and so elevated relatively 85 thereto just when the front side has passed the chute sufficiently to let in the carbid to come above the line to which the inflowing carbid will rise at said rear side by the force of gravity upon the inflowing current from 90 the chute, and consequently the carbid in the pocket behind the chute as carried forward by the pocket will pass free of the cover *b*² and under the lower end of the chute without 95 coming in contact therewith or being liable to be caught between it and the rear side of the pocket. The revolution of the pockets being produced automatically by the movement of the gas-bell is liable to stop just as the carbid begins to pass from the chute into 100 a pocket, and in such case gravity would cause the carbid to run over the rear side of the pocket into the generator unless this arrangement of the chute and pockets or other means were provided to prevent it.

In consequence of the forward inclination of the division-plates the front side of the pocket-chambers has greater area than the rear side and can therefore retain a large part 105 of the pocket contents when the front side by revolution is brought to the horizontal or a little beyond; but the forwardly - curved margin *a*⁶ allows a portion of the contents to be discharged into the generator when the horizontal is reached, or even a little before. 110 The portion so discharged will often produce sufficient gas to cause the bell to rise, and in such case the rotation of the valve stops while the partially-emptied pocket holds back the rest of its contents until the bell descends again.

Metallic baffle-plates *c*, with the parts *c'* and *c*², serve to intercept moisture rising in the induction-tube and condense it below the part of the tube where the valve is situated.

The shaft *a* is provided with a ratchet-wheel or pinion *F*, with which a spring rack-bar *F'* engages. The rack-bar is mounted on the gas-bell and receives movement therefrom. A light spring *f*, attached to the body 130

of the generator, may be used to insure contact of the rack-bar with the wheel. The valve is rotated intermittently by means of the rack and pinion. As a charge of carbid from one of the pockets falls into the water gas is immediately formed, which causes the bell to rise, the rack sliding on the pinion, and as the gas is exhausted from the bell it will fall, causing the rack to engage the pinion and turn the valve until another charge of carbid is dumped into the water.

5 The rotary valve cannot be turned backward, the cover *b'* operating with the pockets of the valve as a pawl with a ratchet-pinion 15 to prevent backward rotation sufficient to empty or partially empty any of the filled pockets.

10 What is claimed is—

1. An induction-tube provided with an inclined chute in combination with a rotary valve having serial peripheral pockets, the chute being inclined downward toward the valve in the direction of the revolution of the pockets and having its discharge end located 25 about at the intersection of a horizontal plane tangent to the top of the circle described by the valve with a vertical plane coincident with the vertical position of the rear side of the pockets when adjacent to said 30 horizontal plane, as specified.

2. An induction-tube having an interior chute in combination with a rotary valve provided with peripheral pockets inclined in the direction of revolution, the chute being 35 inclined downward toward the valve in the direction of the rotation and having its discharge end located at about the intersection of a horizontal plane tangent to the top of the circle described by the valve with a vertical plane coincident with the vertical position of the rear side of the pockets when adjacent to said 40 horizontal plane, as specified.

3. An induction-tube having an interior chute comprising a series of baffle-plates extended alternately from opposite sides of the tube in combination with a rotary valve provided with peripheral pockets, the last plate of the chute being inclined downward toward the valve in the direction of the rotation of 45 the pockets and having its discharge end located at the intersection of a horizontal plane tangent to the top of the circle described by the valve with a vertical plane coincident with the vertical position of the rear side of 50

the pockets when adjacent to said horizontal plane, as specified.

4. An induction-tube provided with an inclined chute in combination with a rotary valve having serial peripheral pockets inclined in the direction of the revolution and 60 separated by division-plates having their peripheral margins curved or projected forward, the valve being arranged close under and behind the discharge end of the chute as specified.

65 5. An induction-tube having an interior chute in conjunction with a rotary valve provided with serial peripheral pockets, the chute being inclined downward toward the valve in the direction of revolution and having its discharge end located at about the intersection of a horizontal plane tangent to the top of the circle described by the valve with a vertical plane coincident with the vertical position of the rear side of the pockets 70 when adjacent to said horizontal plane and a hinged cover for the pockets arranged above and in front of the chute so as to fall upon the valve, as specified.

75 6. An induction-tube provided with an inclined chute in combination with a rotary valve provided with a series of large peripheral pockets adapted and arranged to receive and control the entire mass of carbid passing down the chute, and a hinged cover for the 80 pockets, arranged to have its free end fall over and project into the pockets so as to slide over the front sides thereof in revolution as specified.

85 7. In an apparatus of the class described an induction-tube provided with a chute in combination with a rotary valve provided with peripheral pockets, the chute being inclined downward toward the valve in the direction of the rotation and having its discharge end 90 located at about the intersection of a horizontal plane tangent to the top of the circle described by the valve with a vertical plane coincident with the vertical position of the rear side of the pockets when adjacent to said 95 horizontal plane, and mechanism connecting the valve-shaft with the gas-bell for causing the valve to rotate, as specified.
